TYPOGRAPHICAL COMPOSING MACHINE

Hermann Brandenburg, Berlin-Tempelhof, Germany, assignor to Mergenthaler Linotype Company, Brooklyn, N. Y., a company of New York

Application April 5, 1940, Serial No. 327,989
In Germany June 30, 1939

12 Claims. (Cl. 199—13)

This invention relates to typographical composing machines such as are known commercially under the registered trade-mark "Linotype" and is more particularly concerned with 5 mechanism for adjusting the matrix line length and the slug ejecting mechanism.

Hitherto, when it has been desired to change the length of the line, it has been necessary to carry out an adjustment at four different places 10 on the machine, namely, on the assembler slide, the matrix line delivery carriage, the matrix line stop on the first elevator head and the movable vise jaw. In consequence of errors arising in one or more of these adjustments trouble has frequently occurred, since, if too much or insufficient space is left in the matrix line, the matrices 15 become jammed or tilted, thereby causing the machine to be stopped.

Again, a wrong adjustment may permit metal 20 to penetrate into the intervening spaces between the matrices or even prevent the matrices from being fully introduced into the line thereby again bringing the machine to a standstill.

It is one of the principal objects of the invention 25 to eliminate the above disadvantages and with this and other ends in view the invention consists in the provision of common operating means to adjust the length of the matrix line on the assembler slide and in the vise jaws and 30 to control the slug ejecting mechanism. In addition, means operated from the machine may be provided to return the matrix line stop on the first elevator and the long finger on the delivery carriage to their original positions after movement of the line therefrom.

To carry out the said adjustment, a guide rod 35 associated with the movable vise jaw may be extended the length of the said jaw and of the assembler slide and may be movable in the same direction as the said slide. The said rod may be provided with a fixed stop which is adapted to engage a counter-abutment of the assembler slide. In order to compensate the movement of the vise, it is preferable to divide the guide rod 40 by a coupling which is transversely releasable but quite rigid in the direction of adjustment, so that one portion of the guide rod can partake in the movement when the vise frame is tilted downwardly, while the other portion remains in fixed 45 guides on the machine.

The regulating lever for the slug ejecting mechanism may be adjusted through the adjustable mechanism common to the assembler slide and to the vise jaw by means such as a lifting cam, 50 thereby achieving a further simplification of the

controls. For this purpose a rotatable adjusting handle element may be connected to the assembler slide and to the vise jaw and this element may be provided with a lifting cam engaging with the rod of the slug ejector regulating lever. Advantageously, the lifting cam is divided into steps 5 to enable adjustments of the slug ejector regulating lever to be made to predetermined amounts. Further, the said ejector regulating lever is conveniently joined to its rod by means of a coupling which is so arranged that an independent adjustment of the slug ejecting mechanism may be secured. This is an important matter in those cases where the length of the actual slug cast is such as to require an ejector 15 measurement which is larger than the length of the line characters.

In order that the invention may be more clearly understood one form which it may assume will now be described with reference to the accompanying drawings in which:

Figure 1 is a side view of a portion of a typographical composing machine showing the assembler slide and vise jaws and the upper portion of the first elevator, the intermediate channel, the matrix delivery carriage and the connection to the slug ejecting mechanism, and the common adjusting mechanism;

Figure 2 is a similar view to that of Figure 1 but on a reduced scale, showing more fully the mechanism for returning the matrix line stop and the long finger;

Figure 3 is a section on the line A—B of Figures 1 and 2;

Figure 4 is a horizontal section on the line 35 C—D of Figures 1 and 2;

Figure 5 is a side elevation partly in section of the adjusting mechanism shown in the preceding figures together with the regulating lever for the slug ejecting mechanism;

Figure 6 is a view of the top portion of the regulating lever for the slug ejecting mechanism;

Figure 7 is a longitudinal section on the line 40 E—F of Figure 6, and

Figure 8 is a longitudinal section on the line 45 G—H of Figure 6.

Referring to the drawings:

1 is the assembler slide with the assembler finger 2. The assembler is designated with 3. On the assembler is located a small block 4 having a releasing pin 5, which, through the operation of a two-arm lever 6 actuates the releasing pawl 7, when the assembler ascends, whereby the long finger 8, on the left-hand side of the matrix delivery carriage is released so as to allow 50 55

the same to strike against the line of matrices which is now raised further upwards between the long finger 8 and the short finger 9 of the right matrix delivery carriage. As is already known, the release of the short finger takes place when the assembler reaches its uppermost position, so as to allow the matrix line to slide towards the left through the intermediate channel 10, until it reaches the first elevator head 11. 5 In the first elevator head 11 the matrix line comes up against the displaceable matrix line stop 12 and moves the latter along in front of it. The matrix line stop is formed in known manner as a longitudinally displaceable bail, which is held 15 in its temporary position of adjustment by a brake mechanism, not illustrated in the drawings. When the first elevator ascends into the distributing position, the matrix line stop 12 is engaged by the longitudinally movable pusher 13 and is returned thereby into its initial position 20 by the operation of the link 14 and the lever 15 which is secured to a rock shaft 21 controlled from the cam shaft of the machine. The matrix delivery carriage is returned by means of the link 16 which is attached thereto and to the lever 17. The said lever is fixed to a rock shaft 18. The movement of the carriage to the left is brought about by means of the spring 19 bearing 25 on the lever 20 and secured to the rock shaft 18. 30 The return movement through the link 16 and lever 17 is controlled by means of a cam (not shown) engaging roller 22 on the arm 23 secured to the shaft 18.

The left hand vise jaw 24 of the vise frame 35 is adjustable to the line lengths required as is usual in machines of the kind under consideration. A guide rod 25 extends from the adjusting mechanism for the jaw 24. The said guide rod 25 is subdivided into two parts which are joined 40 by means of a cross pin 26 which at one end is secured to the left hand part of the rod 25 and at the other end engages in an aperture in the right hand part thereof. The result of this is to ensure a coupling which is releasable 45 in the transverse direction, but rigid in the direction of adjustment which makes it possible for the left-hand portion of the guide rod to partake in the movement when the vise-frame is tilted downwardly, whereas the right-hand portion remains in its guideways. To facilitate 50 its engagement, the coupling pin 26 is pointed at its free end.

Upon the rod 25 is mounted a stationary stop 55 27 against which a counterabutment 28 of the assembler slide is adapted to engage. The counterabutment 28 is provided with a finely adjustable screw 29 and is located on a lever 30 rigidly connected to the assembler slide 1, and which extends forward within the reach of the guide rod 60 25. A downwardly rockable detent 31 is located on the stop 27, which detent, after being rocked downwardly, causes the counterabutment 28 to perform a small supplemental movement thereby allowing, as usual, the introduction of a last matrix. One end of the rod 25 is provided with 65 scale divisions, which are employed for adjustment of the desired line length.

The common adjustment of the assembler 1 and of the vise jaw 24 is carried out by actuation 70 of an adjustable handle 32 which is rigidly connected to a shaft 33 which, in turn, is located in a holder 34 of U-shaped cross section. The holder 34 is secured to the front part of the machine close to the assembler. A pinion 35 is mounted at one end of the shaft 33 which is in

mesh with a rack bar 36 and the bar, in turn, is connected at 26 to the guide rod 25, and enables the common adjustment of the assembler slide 1 and the vise jaw 24 to be effected.

The regulating lever for the slug ejecting mechanism bears the reference number 37. It is linked to a lever 38 through a substantially vertically extending rod 39 the said lever 38 being pivotally mounted in the U-shaped holder 34. The lever 38, through a toothed stop 40, rests upon a lifting cam 41 rigidly connected to the shaft 33. The lever 38, near one end, rests upon a detent-like lever 42 which is located on the holder 34, and mounted transversely to the shaft 33, and at the other end bears against a sleeve 43 fast to the shaft 33. 10

The adjusting handle 32 with the shaft 33 is displaceable axially, and when the shaft is pulled out, the sleeve 43 causes the detent-like lever 42 to perform an upward swinging movement 20 whereby the lever 38 is moved into its uppermost position, from which it again drops down upon the lifting cam 41, when the adjusting handle 32, with the shaft 33 are pushed back. According to the adjustment of the lifting cam, its 25 peripheral distance from the axis of the shaft 33 varies so that the lever 38, the rod 39, and the regulating lever 37 are located at different levels in accordance with the adjustment of the assembler slide 1 and of the vise jaw 24. 30

The lifting cam 41 is circumferentially divided into steps in accordance with divisions on the regulating lever 37, which, generally, are of 2 ems in width. In order to set the adjusting handle 32, a setting disc 44 is used, which is integral 35 with the hand grip 32, and is provided with circumferential teeth corresponding in pitch to the scale divisions on the assembler, for example $\frac{1}{2}$ em. When the adjusting handle is pushed back, a blade-like stop 45 provided near the top 40 part of the holder 34, engages the appropriate teeth of the adjusting disc 44, and thereby ensures the maintenance of the selected position. Through the stepwise construction of the lifting cam 41, an unhindered adjustment of the assembler slide and vise jaw in $\frac{1}{2}$ em sizes within a 2 em limit of adjustment of the slug ejecting mechanism can be made.

The regulating lever 37 is loosely connected to the adjusting mechanism by a rod coupling. 50 For this purpose a lateral projection 46 is provided on the upper part of the lever 37, the said projection extending from a housing surrounding the rod 39, in which housing a coupling pin 47 resiliently engages a circumferential groove 55 48 in the guide rod 39. The coupling pin 47 is secured to an angle lever 49 which is pivotally mounted on the projection 46, the said lever being displaceable by a cam-like lever 50, so that under the influence of the lever 50 the coupling 60 pin 47 can be pulled out of the groove 48, against the action of a spring, and the connection between the regulating lever 37 and the rod 39 thus released. The cam-like lever 50 is so arranged that it is capable of being rocked together 65 with the locking lever 51 which locks the regulating lever 37. The lever 51 is usually held in the inactive position by means of a bolt 52. After the release of the bolt 52, the locking lever 51 may be swung out of the way by a spring 53 and 70 the cam lever 50 partaking in the said movement, the coupling pin 47 is withdrawn, so as to effect the release of the regulating lever 37 from the rod 39. The lever 37 is then freely adjustable and a locking hook 54 on the lever 75

51 which is adapted to engage a groove in a serrated disc 55 is used to determine the adjustment which may now be freely carried out. If it is intended again to connect the lever 37 to the rod 39, the locking lever 51 is tightened and bolted. The hook 54 is then released from the serrated disc 55 so as to allow the lever 37 a free movement longitudinally of the rod 39 until the pin 47 drops again into the groove 48.

10 The invention is not restricted to the constructional form illustrated, inasmuch as alterations in detail may be carried out without going beyond the scope of the invention, for instance, other preferred known means of adjustment may 15 be selected; the adjusting mechanism may also be mounted on a different part of the machine. Further, the vise jaw and the assembler slide may also be connected by separate means to a common adjusting mechanism, in which case 20 these separate means may each contain a special fine adjusting mechanism.

Having described my invention, I declare that what I claim and desire to secure by Letters Patent is:

25 1. In a typographical composing machine of the kind referred to the combination of an assembler slide, vise jaws and slug ejecting mechanism, of common operating mechanism to adjust the length of the matrix line in said slide 30 and jaws and to control the adjustment of the ejecting mechanism.

2. In a typographical composing machine of the kind referred to the combination of an assembler slide, vise jaws and slug ejecting mechanism, of common operating mechanism to adjust the length of the matrix line in said slide and jaws and to control the adjustment of the slug ejecting mechanism and means operated from the machine for returning the matrix line 40 stop on the first elevator and the long finger on the delivery carriage to their original positions after movement of the line therefrom.

3. In a typographical composing machine of the kind referred to the combination of an assembler slide, vise jaws and slug ejecting mechanism with common operating mechanism to adjust the length of the matrix line in said slide and jaws and to control the adjustment of said slug ejecting mechanism said slide and jaws being 50 separately connected to said adjusting means.

4. In a typographic composing machine of the kind referred to the combination of an assembler slide, vise jaws and slug ejecting mechanism, a rod connecting said vise jaws and said slide, said rod having a stop thereon engaging an abutment on said slide, a rack bar engaging said rod so that movement thereof will control the matrix line length on said slide and jaws, 55 a rotatable member having a pinion thereon engaging said rack bar, said rotatable member being associated with mechanism to adjust the slug ejector.

5. In a typographical composing machine of the kind referred to the combination of an assembler slide, vise jaws and slug ejecting mechanism, a rod connecting said vise jaws and said slide, said rod having a stop thereon engaging an abutment on said slide, a rack bar engaging 60 said rod so that movement thereof will control the matrix line length on said slide and jaws, a detent on said stop adapted to be rocked so as to cause said abutment to perform a supplemental movement to permit the introduction of 70 an additional matrix, a rotatable member hav-

ing a pinion thereon engaging said rack bar, said rotatable member being associated with mechanism to adjust the slug ejector.

6. In a typographical composing machine of the kind referred to the combination of an assembler slide, vise jaws and a slug ejecting mechanism with a rotatable member, mechanism for controlling the length of the matrix line on said slide and jaws operated by said rotatable member, a lifting cam on said member, 10 a rod operated by said cam, said rod being connected with the slug ejector regulating lever.

7. In a typographical composing machine of the kind referred to the combination of an assembler slide, vise jaws and slug ejecting mechanism with a rotatable member, a rod connecting said slide and said jaws and adapted to control the length of the matrix line thereon, actuated by said rotatable member, a lifting cam on 15 said rotatable member, and separately adjustable means actuated by said cam for adjusting the slug ejector regulating lever.

8. In a typographical composing machine of the kind referred to the combination of an assembler slide, vise jaws and slug ejecting mechanism with a rotatable member, a rod connecting 25 said slide and said jaws and adapted to control the length of the matrix line thereon actuated by said rotatable member, said rod being divided by a transversely releasable coupling so that a 30 portion thereof can tilt with the vise frame and means operated by said rotatable member to adjust the slug ejecting mechanism.

9. In a typographical composing machine of the kind referred to the combination of an assembler slide, vise jaws and slug ejecting mechanism with a rod connecting said slide and said 35 jaws and operable to control the length of the matrix line thereon, a rotatable member adapted to actuate said rod, a stepwise lifting cam on 40 said rotatable member, a rod engaging said cam and the slug ejector regulating lever, the arrangement being such that operation of said rotatable member adjusts the length of the matrix line and enables predetermined adjustments 45 of the slug ejector regulating lever to be made.

10. In a typographical composing machine according to claim 9 a scale on said rotatable member corresponding to predetermined adjustments 50 of the assembler slide or vise jaw.

11. In a typographical composing machine of the kind referred to the combination of an assembler slide, vise jaws and a slug ejecting mechanism with a rotatable member, mechanism 55 for controlling the length of the matrix line on said slide and jaws operated by said rotatable member, a lifting cam on said member, a rod operated by said cam, said rod being adjustable in a coupling on an arm of the slug ejector regulating lever, a pin holding said rod in said coupling, a cam like lever controlling said pin, a locking lever controlling said cam like lever and a hook on said locking lever and a disc having serrations therein to secure said hook while 60 adjustment takes place.

12. In a typographical composing machine of the kind referred to the combination of an assembler slide, vise jaws and slug ejecting mechanism with a rod connecting said slide and said 70 jaws and operable to control the length of the matrix line therein, said rod being divided by a transversely releasable coupling so that a portion thereof can tilt with the vise frame, a rotatable member controlling said rod and having 75

5 a scale thereon to read adjustments thereof, a stepwise cam on said rotatable member, a coupling rod engaging said stepwise cam and having its lower end in an adjustable coupling on an arm of the slug ejector regulating lever, a pin holding said coupling rod in said coupling,

a cam like lever controlling said pin, a locking lever controlling said cam like lever and a hook on said locking lever and a disc having serrations therein to secure said hook while adjustment takes place.

HERMANN BRANDENBURG.
